UNITED STATES PATENT OFFICE

173,139

FLOODLIGHT HOLDER

Max A. Black, Philadelphia, Pa., assignor to M. Black Manufacturing Company, Philadelphia, Pa., a corporation of Pennsylvania

Application May 5, 1954, Serial No. 30,329

Term of patent 14 years

(Cl. D48—20)

To all whom it may concern:

Be it known that I, Max A. Black, a citizen of the United States and a resident of Philadelphia, county of Philadelphia, State of Pennsylvania, have invented a new, original, and ornamental Design for a Floodlight Holder, of which the following is a specification, reference being had to the accompanying drawings, forming a part thereof, wherein:

Figure 1 is a perspective view of a floodlight holder, showing my new design;

Figure 2 is a side elevational view thereof;

Figure 3 is a front elevational view; and

Figure 4 is a rear elevational view.

I claim:

The ornamental design for a floodlight holder, as shown.
